UNITED STATES PATENT OFFICE.

MICHAEL RUDOMETOFF, OF GATTSCHINA, RUSSIA, ASSIGNOR TO FELIX VON BRESSENSDORF, OF LEIPZIG, GERMANY.

PROCESS OF PRODUCING POSITIVE CHROMATIZED COLLOID DESIGNS ON PLATES FOR PRINTING PURPOSES.

SPECIFICATION forming part of Letters Patent No. 741,278, dated October 13, 1903.

Application filed February 24, 1903. Serial No. 144,817. (No specimens.)

To all whom it may concern:

Be it known that I, MICHAEL RUDOMETOFF, a subject of the Czar of Russia, residing at Gattschina, in the Government of Petersburg, 5 Russia, have invented certain new and useful Improvements in Processes of Producing Positive Chromatized Colloid Designs on Plates for Printing Purposes; and I do hereby declare the following to be a full, clear, and exact description of the invention, such as will enable others skilled in the art to which it app pertains to make and use the same.

The property of colloids of combining with chrome salts of the alkaline metals under the influence of light, which causes them to lose their solubility and capability of swelling in water, has been utilized to effect the transfer of photographic negatives to lithographic stones or to metallic plates. This has hitherto been accomplished by means of two different processes—viz., either by a direct transfer or by an intermediate transfer to paper—the colloids principally employed being gelatin or albumen.

25 In order to render the present specification easily intelligible, reference is had to the accompanying drawings, in which similar numerals of reference denote similar parts throughout the several views.

30 Figures 1, 2, and 3 are diagrams representing cross-sections through the plates employed in the processes hitherto known, while Figs. 4, 5, 6, 7, and 8 are a series of diagrams showing the method of carrying out the present process, as hereinafter particularly described.

Referring first to Figs. 1 to 3, in order to effect the direct transfer the plate or stone is first coated with a thin layer of the chromatized colloid—such, for instance, as albumen—and is exposed to the light beneath the negative. The light thus passes through the transparent parts 1 2 3 of the negative, Fig. 1, and converts the layer 4 5 6 thereunder of the chromatized albumen into the insoluble condition. After the negative has been removed and color 7 applied to the whole sensitive layer, Fig. 2, the transfer is developed with water. During this process the surfaces 8, 9, 10, and 11, which had previously been 45 protected against the light by the opaque portions of the negative, will be dissolved, and

thus removed, so that a positive representation consisting of black lines 4, 5, and 6, Fig. 3, will be obtained, which does not, however, lie directly on the plate 12, but on the layer 55 of undissolved colloid 4 5 6.

The second known process for transferring by means of paper is analogous to the above-described one. The only difference is that the chromatized layer is not applied to the 60 plate itself to which the transfers are to be applied, but to the paper, on which the picture is produced in the known manner from the negative. The whole paper, covered with the color or printer's ink, is then developed 65 with water, and a positive picture remains on the paper as this is attained in Fig. 3 by means of a direct transfer.

The present process is carried out in the following manner and illustrated in Figs. 4 70 to 8: The paper 13; Fig. 4, covered with a layer of the chromatized colloid, such as albumen, is exposed beneath the negative. The parts 17 18 19 of the colloid layer lying underneath the translucent parts 14 15 16 of the 75 negative will be rendered insoluble. In order to transfer this copy to the stone or metal plate, it is moistened at the back, or if this cannot be advantageously done—for instance, in the interest of an exact register for the 80 colors—the copy may be kept dry and the stone moistened with water, as illustrated in Fig. 5. The copy is then rolled or otherwise pressed onto the plate 20, to which it adheres, and then the paper is moistened at the back 85 until the moisture penetrates the same and dissolves the albumen. This permits of the paper being removed from the plate 20, on which the parts 21, 22, 23, and 24 of the colloid layer will remain, which had previously 90 been lying under the opaque parts of the negative—i. e., the parts lying between those parts which had been rendered insoluble—viz., 17 18 19, as shown in Fig. 6. After the chromatized albumen thus transferred to the 95 plate 20 has dried the whole plate is entirely covered with color, Fig. 7. If the plate thus prepared be washed with water, the albumen will dissolve and with the color on it will come off the plate, while only those parts will 100 remain on the plate as a positive picture which were situated between the soluble al-

bumen parts 21 22 23 24, and this layer of color 26 27 28 will lie directly on the plate or stone 20 in contradistinction to the process described with reference to Figs. 1 to 3.

5 This present process or method of transfer renders it possible to apply the negative copy in a dry condition to the moistened plate or stone, which is of great importance in the interest of an exact register in chromolithographic work. In addition to this advantage retouching or toning-down of parts of the picture may be much more easily and conveniently carried out than has hitherto been the case, inasmuch as the stone or plate may be 10 sprinkled with a solution of gum-arabic or albumen before the color is rolled on, and thus any desired part of the design may be toned down to any desired degree. In addition to this the copy may be touched up with 15 a pen or brush (with a solution of gum-arabic or albumen) before the color has been applied, and the color may be added after the alterations have been allowed to dry. Thus corrections may be easily made which could 20 hitherto only be effected with difficulty with the aid of a point or scraper.

The present process differs from those previously mentioned in that the interstices between the lines of the drawing (negative) 25 which consists of a soluble layer of the chromatized colloid are transferred to the plate or stone and not the lines (positive) of the drawing and that finally a positive is attained the color of which lies directly on the plate 30 itself.

35 I claim as my invention—

1. The improved process for producing positive chromatized colloid designs on plates for printing purpose which consists first in

producing a layer of chromatized colloid, secondly in superposing a negative on the said layer, thirdly in exposing the colloid layer to light through the negative, fourthly in transferring the colloid layer to the printing-plate and fifthly in removing the backing and parts 45 of the layer from the printing-surface, substantially as set forth.

2. The improved process for producing positive chromatized colloid designs on plates for printing purposes which consists first in 50 coating a temporary backing with a layer of chromatized colloid, secondly in superposing a negative on said layer, thirdly in exposing the layer to light through the said negative, fourthly in causing the surface of the layer 55 to adhere to the printing-surface and fifthly removing the backing and exposed parts from the printing-surface leaving the unexposed parts thereon, substantially as set forth.

3. The improved process for producing positive chromatized colloid designs on plates for printing purposes which consists first in 60 coating a temporary backing with a layer of chromatized colloid, secondly in superposing a negative on said layer, thirdly in exposing 65 the layer to light through the said negative, fourthly in applying the surface of the undeveloped design to a moistened printing-surface, fifthly washing off the backing from the design, sixthly applying the printing me- 70 dium to the layer, and finally washing away the soluble parts, substantially as set forth.

In witness whereof I have hereunto set my hand in presence of two witnesses.

MICHAEL RUDOMETOFF.
